UNITED STATES PATENT OFFICE.

ANTHONY ISKE, OF LANCASTER, PENNSYLVANIA.

SECRETARY-TABLE.

SPECIFICATION forming part of Letters Patent No. 233,766, dated October 26, 1880.

Application filed June 9, 1880. (No model.)

To all whom it may concern:

Be it known that I, ANTHONY ISKE, a citizen of the United States, residing at Lancaster, in the county of Lancaster and State of Pennsylvania, have invented certain new and useful Improvements in Secretary-Tables; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention relates to tables which are readily convertible into secretary-desks by raising a pigeon-holed portion or compartment above the top thereof.

The said invention consists in the peculiar 20 devices employed for raising and lowering said pigeon-holed part and for locking it in its upper and lower positions.

In the accompanying drawings, Figure 1 represents a perspective view of my improved 25 table and secretary, the front drawer being slightly pulled out and the movable part raised. Fig. 2 represents a vertical section through the same; and Fig. 3 represents a vertical section through the article when arranged for use as a table only. Fig. 4 represents a detail view of the lever, rock-shaft, and arm.

A designates a table, supported on legs a , and having its hollow body divided into two 35 compartments, A' A^2 , by a swinging partition, a' , which is parallel to the front of said table. In the forward compartment, A' , an ordinary drawer, B, works in and out on guide-strips b . When forced entirely into the table it 40 presses against swinging partition a' , and forces the latter into a backwardly-inclined position. While in this position the said partition rests upon a ledge, c , Fig. 3, of a box or pigeon-holed part, C; and locks the latter in 45 place. The top of said box is then flush with the top a^2 of the table, so that the two practically form a continuous and even table-top. When not thus locked the part C is free to be moved up and down in suitable guideways 50 in the sides of compartment A^2 . This movement is effected by means of a lever, D, of the first kind, which is mounted on a rock-shaft, E, parallel to the front of the table, and mounted in the ends thereof under the top a^2 .

55 The handle d of said lever extends to the front

of the table, and its rear end, d' , extends under the pigeon-holed box or apartment C, so that when said handle is depressed said box rises above the top of the table. Said end d' is rounded, so that when the box has reached 60 its uppermost position the said lever will turn into the position shown in Fig. 2, with the handle end inclined slightly backward, and the tip of the lifting end d' holding said box upward. While in this position said box or 65 apartment is effectually locked by said lever until the handle end of said lever is drawn forward again. Said lever is preferably arranged at or near one end of rock-shaft E.

To provide more effectually for the support 70 of box or apartment C, I employ an arm, F, Fig. 4, on the other end of said rock-shaft, which has a similar operation to that of the rearward part of lever D. The forward part of said lever is provided with an upwardly-extending 75 stud, d^2 , which presses against the bottom of drawer B, so as to increase the difficulty of withdrawing the latter. This tends to prevent the accidental liberation of the pigeon-holed box or apartment C. Before said apartment or box can be raised the drawer B must be pulled slightly out so as to release the swinging partition a' . The latter then swings forward, freeing said box, and the lever may be operated as described.

Having thus fully described my invention, what I claim as new, and desire to secure by Letters Patent, is—

1. In combination with a table, having a fixed top, a^2 , and vertically-sliding pigeon-holed part C; the lever D, provided with curved end d' , and arranged to lock said part C in its uppermost position, substantially as set forth.

2. The drawer B, in combination with hinged partition a' and sliding part C, provided with a projecting ledge, said drawer, when pressed inward, serving to force said partition into engagement with said part C, substantially as set forth.

3. In combination with table A; movable part C, and hinged partition a' ; the drawer B and lever D, having stud d^2 , substantially as set forth.

In testimony whereof I affix my signature 105 in presence of two witnesses.

ANTHONY ISKE.
